DECEPTION ELEMENT FOR HYPODERMIC SYRINGES

Daniel Gabriel, Bonny Blue, Va.

Application February 5, 1954, Serial No. 408,358

8 Claims. (Cl. 128—215)

This invention relates to hypodermic syringes for use in performing injections into a patient. More particularly, the invention deals with what I term a deception element for devices of this type and kind, that is to say, an element which covers and envelopes the needle of the syringe and provides a relatively large body therearound, so as to relieve the patient of the optical or mental fear of having a needle pierced into any part of the body.

Still more particularly, the invention deals with an element of the character described, which creates a secondary pressure upon the body, thus minimizing the feeling of the needle injection into the body.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is a diagrammatic side view of one type of syringe showing, in section, one form of deception element arranged thereon and indicating contracted position of the element in dotted lines.

Fig. 2 is a sectional view through a modified form of element, indicating the element in different position in dotted lines and diagrammatically showing the needle end only of a syringe.

Fig. 3 is a side elevation of another form of element which I employ detached, with part of the construction broken away and in section.

Fig. 4 is a bottom plan view of the structure shown in Fig. 3; and

Fig. 5 is a sectional detailed view of the upper end portion of an element, illustrating a different method of attachment to a syringe, part of the syringe being illustrated in elevation.

While my deception elements are applicable for use on syringes of various types and kinds, in illustrating one adaptation of my invention I have shown at 10, in Fig. 1 of the drawing, a Luer-lock-type of syringe, in which the usual plunger 11 is movably mounted. At 12 I have shown the Luer-lock coupling of the syringe, at 13 the coupling end of a needle 14, the end 13 being attachable with the Luer-lock 12, as with other devices of this type and kind. At 15 I have shown, in Fig. 1 of the drawing, in section, one of my improved deception or enveloping elements, the element 15 comprising a flexible wall tube composed of rubber or plastic material having an inwardly curled or annular beaded upper end portion 16 adapted to securely grip the Luer-lock 12 in supporting the element 15 on the syringe with the lower end 17 of the element protruding slightly beyond the lower pointed end 18 of the needle 14. The lower end portion of the element 15 has, on its inner surface, an insert 19 with a downwardly contracted bore 20 to guide the element 15 in its movement upwardly over the needle 14 from the extended position shown in full lines to a contracted position, as diagrammatically illustrated in dotted lines in

2

Fig. 1 of the drawing. The insert 19 may be composed of plastic or other material.

In the movement of the element 15 into its contracted position, the characteristics of the flexible tubular body is such as to roll up over the syringe 10 in the manner diagrammatically shown and can be readily returned to its normal extended position by manual operation. In other words, this folding operation simulates that of the stripping of the finger of a rubber glove from the finger of the hand with the exception that no pressure is required. The firm engagement at 16 will allow the freely flexing tube to fold in the manner diagrammatically illustrated. The upper portion of the element 15 has a vent passage 21 for discharge of air in the contracted movement of the element.

In Fig. 2 of the drawing, I have shown a modified form of element 22 which differs from the element 15 in being conical in form, that is to say, the lower end portion 23 is of greater diameter than the upper inwardly curled end portion 24, the end portion 24 being similar to the curled end 16. At 25 I have shown a vent, similar to the vent 21. In Fig. 2, the structure is further modified in providing, at the lower end 23 of the element 22, a transverse rubber diaphragm 26 suitably fixed at the periphery of the element 22, as seen at 27, the diaphragm completely concealing the needle 14', similar to the needle 14 and, in operation, the needle pierces the diaphragm, the diaphragm being of such structure as to seal itself after the needle has been withdrawn therefrom, or returned to the position shown in Fig. 2. With the structure shown in Fig. 2, the element 22, in contraction, will move substantially into the position indicated in dotted lines in said figure.

In Figs. 3 and 4 of the drawing, I have shown another adaptation of my invention, wherein the element 28 is somewhat conical in form and is preferably moulded from highly flexible rubber or plastic material to represent an amusing character, such for example as a little man having his hands 29 disposed over his ears and with a smiling face 30. The upper head or hat end 31 of the element will have the inturned or rolled end 32, similar to the ends 16 and 24 for mounting on the syringe with a vent 33 closely adjacent said end. The lower flared end portion 34 of the element can be shaped and otherwise characterized to represent the feet 35 of the little man.

The end 34 will preferably be of elliptical form, as noted in Fig. 4 of the drawing; whereas, the body portion of the element can be cylindrical, as evident from the line 36 of Fig. 4, but contracted to the upper end to form a substantially conical portion which will contract substantially in the manner illustrated in Fig. 2 of the drawing.

In Fig. 5 of the drawing, I have shown at 37 the upper portion of an element which may be similar to any one of the elements 15, 22, 28 and which differs from the other elements in having a special beaded upper end 38, grooved, as seen at 39, to receive an annular flange portion 40 formed on any suitable part of the syringe structure. In the present showing, the flange 40 is formed on part of a Luer-lock casing 12', similar to the Luer-lock 12. At 41 is shown a vent, similar to the other vents employed in order to relieve air in movement of the element into its raised or contracted position.

The type of device diagrammatically portrayed in Fig. 3 of the drawing is designed for use primarily in dealing with injections given to small children so as to draw attention of the child to the deceptive element as a little character who is going to help them in their momentary trouble. Most people, however, rather fear the approach of a needle to the body in the operation of giving them an injection, thus with other more modified forms of

devices, such as the elements 15 and 22, here again, the needle is shielded and a relatively large body is brought into engagement with the flesh, so as to remove the optical or mental fear of the injection operation.

It will be understood that various types and kinds of deceptive or enveloping elements can be utilized on syringes of many types and kinds. However, in all instances, it will be desirable to employ an element movable longitudinally with respect to the needle so as to contract in projection of the needle into the body, the degree of contraction being governed solely by the extent of insertion of the needle into the body, it being understood that pressure of the element upon the body moves the same into its collapsed or contracted positions.

Having fully described my invention, what I claim as new and desire to secure by Letters Patent is:

1. In hypodermic syringes employing a syringe casing with a needle disposed at one end portion thereof, an element mounted on the casing and having a large diameter end portion enveloping the needle of the syringe to substantially conceal said needle, said element being in the form of an elongated yieldable walled tubular body, the wall of said element being foldable and movable longitudinally of the casing and needle in the operation of injecting the needle into the body of a patient, and means, at the upper end portion of said element, for positioning the element on the syringe.

2. In hypodermic syringes employing a syringe casing with a needle disposed at one end portion thereof, an element mounted on the casing and having a large diameter end portion enveloping the needle of the syringe to substantially conceal said needle, said element being in the form of an elongated yieldable walled tubular body, the wall of said element being foldable and movable longitudinally of the casing and needle in the operation of injecting the needle into the body of a patient, means, at the upper end portion of said element, for positioning the element on the syringe, and a rubber diaphragm normally closing the end of the element beyond end limits of said needle.

3. In hypodermic syringes employing a syringe casing with a needle disposed at one end portion thereof, an element mounted on the casing and having a large diameter end portion enveloping the needle of the syringe to substantially conceal said needle, said element being in the form of an elongated flexible walled tubular body, the wall of said element being movable longitudinally of the casing and needle in the operation of injecting the needle into the body of a patient, means at the upper end portion of said element for positioning the element on the syringe, and the upper end portion of said element having a vent passage.

4. In hypodermic syringes employing a syringe casing with a needle disposed at one end portion thereof, an element mounted on the casing and having a large diameter end portion enveloping the needle of the syringe to substantially conceal said needle, said element being in the form of an elongated flexible walled tubular body, the wall of said element being movable longitudinally of the casing and needle in the operation of injecting the needle into the body of a patient, means at the upper end portion of said element for positioning the element on the syringe, and means at the lower portion of said

element for guiding the element along the needle of the syringe.

5. A deception element for enveloping the needle of a hypodermic syringe, said element comprising an elongated tubular yieldable walled body materially greater in diameter than the diameter of said needle, means, at one end portion of said element, arranged upon the syringe for fixedly positioning said end of the element on the syringe, the other end portion of said element normally extending beyond the needle end, and the yieldable wall of said tubular body being foldable and movable longitudinally of the syringe in the operation of injecting the needle.

6. A deception element for enveloping the needle of a hypodermic syringe, said element comprising an elongated hollow yieldable walled body materially greater in diameter than the diameter of said needle, means, at one end portion of said element, arranged upon the syringe for fixedly positioning said end of the element on the syringe, the other end portion of said element normally extending beyond the needle end, the yieldable wall of said hollow body being foldable and movable longitudinally of the syringe in the operation of injecting the needle, and said second named end portion of said element being of greater diameter than the first named end portion.

7. In hypodermic syringes employing a syringe casing with a needle disposed at one end portion thereof, an element mounted on the casing and having a large diameter end portion enveloping the needle of the syringe to substantially conceal said needle, said element being in the form of an elongated, flexible, walled, hollow body, the wall of said element being foldable and movable longitudinally of the casing and needle in the operation of injecting the needle into the body of a patient, means at the upper end portion of said element for positioning the element on the syringe, and the body portion of said element being shaped to represent a predetermined character.

8. In hypodermic syringes employing a syringe casing with a needle disposed at one end portion thereof, an element mounted on the casing and having a large diameter end portion enveloping the needle of the syringe to substantially conceal said needle, said element being in the form of an elongated, flexible, walled, hollow body, the wall of said element being foldable and movable longitudinally of the casing and needle in the operation of injecting the needle into the body of a patient, means at the upper end portion of said element for positioning the element on the syringe, the body portion of said element being shaped to represent a predetermined character, and the lower portion of the characterized body being elliptical in form.
